DESIGN FOR A COMBINED TABLE LAMP AND STAND OR THE LIKE

Samuel J. Kaz, Chicago, Ill.

Application April 3, 1933. Serial No. 47,679

Term of patent 3½ years

To all whom it may concern:

Be it known that I, SAMUEL J. KAZ, a citizen of the United States, residing at Chicago, in the county of Cook and State of Illinois, have invented new, original, and ornamental Design for a Combined Table Lamp and Stand or the like, of which the following is a specification, reference being had to the accompanying drawings, forming part thereof.

Fig. 1 is a side elevation of my novel design for a combined table lamp and stand or the like.

Fig. 2 is a front elevation of the same.

Fig. 3 is a perspective view of the same.

I claim:

The ornamental design for a combined table lamp and stand or the like, substantially as shown.

SAMUEL J. KAZ.
